[57] **CLAIM**

The ornamental design for a cellular phone holding and transporting device, as shown and described.

DESCRIPTION

FIG. 1 is a front plan view of the cellular phone holding and transporting device of the present invention;

FIG. 2 is a back plan view of the cellular phone holding and transporting device of FIG. 1;

FIG. 3 is a left side plan view of the cellular phone holding and transporting device of FIG. 1;

FIG. 4 is a right side plan view of the cellular phone holding and transporting device of FIG. 1;

FIG. 5 is a top plan view of the cellular phone holding and transporting device of FIG. 1; and,

FIG. 6 is a bottom plan view of the cellular phone holding and transporting device of FIG. 1.

The interior pad as best seen in FIG. 5 is parallel to the base having a continuous thickness consistent with that shown in FIG. 2.
